UNITED STATES PATENT OFFICE.

WILLIAM L. MURPHY, OF SAN FRANCISCO, CALIFORNIA, ASSIGNOR TO MURPHY DOOR BED COMPANY, OF SAN FRANCISCO, CALIFORNIA, A COPARTNERSHIP CONSISTING OF WILLIAM L. MURPHY AND WILLIAM K. WHITE.

FOLDING BED.

Application filed August 26, 1920. Serial No. 406,149.

To all whom it may concern:

Be it known that I, WILLIAM L. MURPHY, a citizen of the United States, and a resident of the city and county of San Francisco and State of California, have invented a new and useful Folding Bed, of which the following is a specification.

My invention relates to folding beds of the roller type.

10 An object of the invention is to provide a bed of the type described which is free from the tendency to tip over when folded. This is a fault commonly found in this type of bed. Another object is to provide a folding bed characterized by the tendency of the folding structure to remain in the folded position by reason of its weight. Another object is to provide a bed of the character described characterized by ample 15 low space. Another object is the provision of a folding bed which automatically locks itself in the unfolded position so that it cannot be accidentally released, and which is at the same time readily disengaged for 20 folding.

25 The invention possesses other objects and features of advantage, some of which, with the foregoing, will be set forth in the following description of the preferred form of 30 my invention which is illustrated in the drawings accompanying and forming part of the specification. It is to be understood that I do not limit myself to the showing made by the said drawings and description, 35 as I may adopt variations of the preferred form within the scope of my invention as set forth in the claim.

40 Referring to the drawings: Fig. 1 is a side elevation of the bed lowered or unfolded. No upholstered mattress is shown. Fig. 2 is a sectional view of the head of the unfolded bed, taken in the plane indicated by the line 2—2 of Fig. 1. A portion is broken away to reduce the width of the view. 45 Figs. 3 and 4 are side elevations of the head end of the bed when folded and unfolded respectively. In both figures portions are omitted but indicated in light dotted lines. Fig. 5 is a transverse sectional view showing an elevation of one side of the head of the bed. The plane of section is indicated by the line 5—5 of Fig. 4. Fig. 6 is a side elevation of a modified bed structure.

50 In terms of broad inclusion my bed com-

prises a relatively short base frame, upon 55 which the mattress-supporting or folding spring frame is mounted so that it may be turned down to the horizontal position of use or up to the vertical folded position. A sliding or rolling connection between the 60 spring or folding frame and base permits easy movement of the former and provides no fulcrum during the folding movement whereby a tipping force may be applied to the base. Such a fulcrum is reached only 65 at the extremes of the movement of the folding frame, that is, when the frame is turned down to the position of use, and when it extends vertically upward in the folded position. In the first position the 70 outer end is supported on the floor by appropriate legs at the moment the fulcrum is reached so that the structure as a whole 75 is fully stable. The folding frame at this point is automatically locked upon the base 80 so that accidental movement is impossible.

In the second or folded position the 85 mounting of the frame is such that its center of gravity is over the middle of the base frame, and at a distance from the floor not greater than the length of the supporting 90 base. In either position, movement to the other, necessitates a slight raising of the frame by movement up a short incline. The weight of the frame therefore tends to 95 give full stability in the folded and unfolded positions, and because of the rolling connections between the folding frame and the base, no fulcrum or purchase upon the base can be secured during the movement 100 of the folding frame, and hence the base cannot be tipped over during operation of the bed. Means are also provided for balancing the folding frame in the base, and for automatically folding and unfolding the 105 head frame when the spring frame is moved.

The base of my bed comprises side frames formed preferably of tubing in inverted U-form to provide short side rails 2 and legs 3 for the bed. The tubing is connected by 100 bracing frame 4 preferably cast about the tubing, so that light, side frames are provided, on which to mount the folding or spring frame 6, which carries the spring fabric 7 on which the mattress of the bed 105 is supported. The side frames are mounted on casters 8 to facilitate bodily movement of the bed structure either when fold-

ed or unfolded, and are connected together by cross rails 9, which are conveniently placed near the bottom.

Rigidly fixed on the inner side of each side frame are slide-ways 10 and 11. Slide-way 10 comprises a plate having a substantially horizontal slot 12 therein, which is inclined downwardly from the middle toward the rear or head of the bed. Slide-way 11 is also formed with a slot 13 which begins at a point vertically below the rear end of the slot 12, and slants upwardly and rearwardly at an angle of, say 45°, terminating on a level with the rear end of slot 12. The upper end 14 of slot 13 is turned nearly to the horizontal as best shown in Fig. 3.

Fixed on each side of the folding frame 6 are spaced studs 16 and 17, preferably provided with rollers 18 and 19 respectively adapted to be engaged in slots 12 and 13 respectively. In order to prevent lateral disengagement of the rollers, they are grooved, being preferably made in two pieces to permit assembly in the grooves. The folding frame is thus supported on the base by a sliding or rolling connection, and the parts are so arranged and proportioned that the folding frame may readily be moved to vertical or horizontal position as shown in Figs. 3 and 4 respectively. A fixed headboard 21 is arranged on the folding frame and a counterweight 22 is preferably disposed across this head board.

In moving from the folded or vertical position shown in Fig. 3 to the unfolded or horizontal position shown in Fig. 4, the turning motion is about the studs 16 which move forward in slide-ways 10, while the studs 17 move upwardly in slide-ways 11. A small resistance to the initiation of this movement is offered because the rear portion of the slot in the slide-way 10 is inclined, as already explained, and of course the frame tends to remain at the lowest point. A small amount of pull toward the operator, however, causes the roller 18 to move up on the slide-way, too fast a movement being avoided by the counterbalancing weight. The heavy dotted lines in Fig. 3 show the folding frame partially lowered. As the folding frame approaches horizontal position, the stud 16 again moves to the low end of the slide-way and stud 17 seats in the nearly horizontal portion 14 of the slide-way 11, in which position the weight of the frame acting on the inclined slide-way 10, tends to hold it. So positioned a perfectly stable bed is provided, since no downwardly acting force likely to be exerted on the head of the frame is sufficient to displace the stud 17 from its seat. The folding frame locks automatically in the horizontal position, so

that accidental pivotal movement or folding of the frame is impossible. To fold up the bed the foot end is pulled outwardly and raised. This disengages the stud 17 from its seat and permits it to move downwardly in the slide-way 11, the frame pivoting on stud 16 moves forward and then backward in the slide-way 10, to finally gravitate to the rear end as the frame approaches the vertical. As soon as the roller 18 starts downwardly in the right hand half of the slide-way (viewed as in Fig. 3) the weight of the folding structure tends to complete the folding movement.

A folding head frame 23 is pivoted on the fixed head frame and connected by link 24 to a fixed point on the base, so that when the frame 6 is folded, the head frame is turned automatically into parallelism therewith. The space between the folding head frame and the frame 6 in the folded position, as shown in Fig. 3 provides ample pillow room, so that the pillows need not be disturbed prior to the folding. A pivoted leg 27 on each side of the foot end of the folding frame swings in close to the folding frame when the bed is folded.

In Fig. 6, I have shown a modified structure in which the head board 23 is maintained in substantially vertical position during movement of the bed frame, by a guide rod 28, preferably fixed to the cross rail midway between the side frames. An eye 29 fixed to the head board slidably engages the guide rod.

I claim:

A folding bed comprising a base having on each side a slide-way having a substantially horizontal forward portion and a downwardly inclined rearward portion, and an upwardly and rearwardly inclined slide-way having a substantially horizontal rearward portion, the rear end of said first slide-way being disposed vertically above the forward end of the inclined slide-way and horizontally in front of the rearward end of the inclined slide-way, and a flat bed frame mounted on said base and engaging said slide-ways and adapted to be moved from a horizontal to a vertical position and vice versa, said bed frame in its vertical position engaging the rear end of said first-named slide-way and the front end of the second-named slide-way and in its horizontal position engaging the rear ends of both said slide-ways whereby stability of the said bed frame is achieved in both positions.

In testimony whereof, I have hereunto set my hand.

WILLIAM L. MURPHY.
